C. HITTINGER.

CAR STOVE EXTINGUISHER.

No. 289,657.

Patented Dec. 4, 1883.

ATTORNEY

UNITED STATES PATENT OFFICE.

CHRIST HITTINGER, OF DAYTON, OHIO.

CAR-STOVE EXTINGUISHER.

SPECIFICATION forming part of Letters Patent No. 289,657, dated December 4, 1883.

Application filed August 15, 1883. (No model.)

To all whom it may concern:

Be it known that I, CHRIST HITTINGER, a citizen of the United States, residing at Dayton, in the county of Montgomery and State 5 of Ohio, have invented a certain new and useful Improvement in Car-Stove Extinguishers; and I do hereby declare that the following is a full, clear, and exact description of the invention, which will enable others skilled in the art 10 to which it appertains to make and use the same, reference being had to the accompanying drawings, and to the letters of reference marked thereon, which form a part of this specification.

15 My invention relates to an improved device for extinguishing the fire in a car-stove when by accident the car is overturned; and it consists, in its essential feature, in a pivotal reservoir which is discharged by its own gravity 20 when the car to which the same is attached is overturned.

I attain the object by the mechanism illustrated in the accompanying drawings, in which—

25 Figure 1 is a side view of the extinguisher as attached to the floor of a passenger-coach. Fig. 2 is a top view of the segmental cog as attached to the stem of the stop-cock.

30 A represents the floor of a passenger-coach to which the hangers B B' are bolted.

M represents a stove, which may be of a variety of forms, the only essential feature being that a hole in the side, near the top, must be provided for a pipe.

35 On both ends of the reservoir C are hollow bearings, which are pivoted in the hangers. These bearings are attached to the cylindrical reservoir, near the top of the same. Water is poured into the reservoir through a hole in 40 the top (not illustrated) until it reaches the height of the dotted line, and when closed the vessel is air-tight. The ordinary check-valve, D, prevents any escape in that direction, and the ordinary stop-cock, E, likewise closes the discharging-orifice.

45 The flexible pipe I is attached to the pipe outside of the check-valve, and is connected with a pipe leading from a Westinghouse air-pump. By this means air is forced into the 50 space above the water, giving a pressure equivalent of that used to operate the car-brakes. Into the right bearing is screwed the curved pipe F, which terminates near the

bottom of the reservoir, and thus the air is prevented from escaping from the reservoir 55 until the water is exhausted. To the bearing to the right is attached the ordinary stop-cock, E, and to the stem of which is loosely attached the segmental beveled cog H, (top view at Fig. 2,) which is supported on the nut on the end 60 of the stem. A portion of the hub is cut away, and within which space a lug of the stem of the stop-cock plays, and therefore slight oscillation of the reservoir does not move the plug of the stop-cock. 65

To the hanger E' is bolted the segmental beveled cog G, which engages cog H, previously described, and by which gear the valve is opened by the partial rotation of the reservoir in its bearings. The flexible tube J is 70 connected to the iron pipe K, and to this the rose L is connected within the stove, immediately above the fire-box. The check-valve and stop-cock are rigidly attached to the bearings of the reservoir, and the flexible 75 tubes I and J admit of a comparatively free movement of the reservoir. If metallic connections alone are made, stuffing-boxes must be provided for the connections at both ends.

The operation is thus: Fill the reservoir 80 with water to the dotted line; then turn in the air from the air-pump, which connection may be permanent. The contained water is subjected to great pressure, and when the car overturns the gravity of the reservoir causes 85 it to swing in its bearings, thereby opening the stop-cock, which admits of the jetting of the water from the rose onto the fuel contained in the fire-box of the stove, and thus the fire is extinguished. 90

Having fully described my invention, what I claim, and desire to secure by Letters Patent, is—

The combination and arrangement, substantially as set forth, of the reservoir C, hangers 95 B B', check-valve D, stop-cock E, segmental cog-gear G H, pipe F, and tubing to connect with air-pump and rose L within the fire-box of a stove.

In testimony that I claim the foregoing as 100 my own I affix my signature in presence of two witnesses.

CHRIST HITTINGER.
